UNITED STATES PATENT OFFICE.

ISAAC STROUSE, OF NEW HAVEN, CONNECTICUT.

DESIGN FOR A CORSET.

SPECIFICATION forming part of Design No. 12,693, dated January 10, 1882.

Application filed December 15, 1881. Term of patent 7 years.

To all whom it may concern:

Be it known that I, ISAAC STROUSE, of New Haven, in the county of New Haven and State of Connecticut, have invented a new Design for Corsets; and I do hereby declare the following, when taken in connection with the accompanying drawing and the letters of reference marked thereon, to be a full, clear, and exact description of the same, and which said drawing constitutes part of this specification, and represents a side view, showing the hip-section complete.

This invention relates to a design for the ornamentation for that part of a corset commonly called the "hip-section"—that is to say, the part of the corset between the front and back, and which extends from under the arm down over the hip; and the design consists in the representation of cords or ribs in series, as shown in the accompanying illustration and hereinafter described.

Transversely across the section is a series of ribs—*a* at the top, *b* at the center, and *d* at the

bottom. Between the lower series, *d*, and the middle series, *b*, the space is filled by ribs *e*, 25 running from the center diagonally downward and backward, and similar ribs, *f*, running from the center downward and forward. The space between the middle series, *b*, and the upper series, *a*, is filled by diagonal ribs running 30 downward and forward, as shown in the accompanying illustration.

I claim—

The design for the hip-section of a corset, consisting of the transverse series of ribs *a b d*, the 35 space between the series *b d* filled by ribs *e f*, running diagonally respectively from the center downward and backward and downward and forward, the space between the series *b* and *a* filled by ribs running diagonally downward and forward, as shown in the accompanying illustration.

ISAAC STROUSE.
